CLAIM

The ornamental design for a waterproof bag as shown and described.

DESCRIPTION

FIG. 1 is a perspective view of a waterproof bag showing my new design;

FIG. 2 is a perspective view of the waterproof bag in another angle;

FIG. 3 is a front view of the waterproof bag;

FIG. 4 is a rear view of the waterproof bag;

FIG. 5 is a left view of the waterproof bag;

FIG. 6 is a right view of the waterproof bag;

FIG. 7 is a top plan view of the waterproof bag;

FIG. 8 is a bottom plan view of the waterproof bag;

FIG. 9 is an enlarged view of the reference sign 9 of FIG. 2 thereof;

FIG. 10 is an enlarged view of the reference sign 10 of FIG. 5 thereof; and,

FIG. 11 is an enlarged view of the reference sign 11 of FIG. 8 thereof.

The dot-dash broken lines encircling portions of the waterproof bag in FIGS. 2, 5, and 8, and illustrated in enlarged views in FIGS. 9, 10, and 11 form no part of the claimed design.

1 Claim, 11 Drawing Sheets
